W. J. SWARTZ & E. H. WAUGH,
STACKER FOR CONFECTIONS.
APPLICATION FILED MAR. 13, 1914.

1,241,165.

Patented Sept. 25, 1917.

UNITED STATES PATENT OFFICE.

WILLIAM J. SWARTZ AND EDWARD H. WAUGH, OF SEATTLE, WASHINGTON, ASSIGNEES
TO AUTOMATIC CANDY MACHINE COMPANY, A CORPORATION OF WASHINGTON.

STACKER FOR CONFECTIONERY.

1,241,165.

Specification of Letters Patent. Patented Sept. 25, 1917.

Application filed March 13, 1914. Serial No. 824,441.

To all whom it may concern:

Be it known that we, WILLIAM J. SWARTZ and EDWARD H. WAUGH, citizens of the United States of America, residing at Seattle, in the county of King and State of Washington, have invented certain new and useful Improvements in Stackers for Confections, of which the following is a specification.

10 Our invention has for one of its objects to provide a construction of the above type wherein the articles are stacked in a more efficient manner.

15 A further object resides in a novel provision for supporting one or more stacks of articles.

20 Other objects will be set forth as our description progresses and those features of construction, arrangements and combinations of parts on which we desire protection, will be succinctly defined in our annexed claims.

25 Referring to the accompanying drawings, illustrating a preferred embodiment of our invention, wherein like characters of reference indicate like parts throughout:

Figure 1 is a side elevation of our improved stacker.

Fig. 2 is a top plan view of the stacker 30 and a fragmentary portion of the advancing mechanism.

Fig. 3 is a vertical section thereof.

Fig. 4 is a fragmentary horizontal section of the stacker.

35 Fig. 5 is a detailed perspective of a portion of the swing frame in which the carrier for the article support is slidably mounted.

Referring to the drawings by numerals of reference, 1 indicates mechanism for ad-

40 vancing articles to a support 2, which latter is arranged on a carrier 3, mounted for movement at an angle to mechanism 1, whereby the said support 2 can be lowered as the stacking of the articles thereon progresses. The advancing mechanism 1, as herein shown, comprises an endless apron which is carried upon rollers 5, fixed to shafts 5', journaled on a stand 6. Said mechanism may be operated by any suitable intermittent motion device.

50 Reference numeral 14 indicates a swing frame mounted at the delivery end of advancing mechanism 1, the same comprising side members 14', rigidly connected by an

integral tie bar 14" and provided with rearwardly extending arms 15 which are pivoted at 16 on the upper portion of stand 7 and provided with stop lugs 14^a for seating on stand extensions 7^a.

Side members 14' are provided with slide-ways conveniently formed by spaced ribs 17, arranged to hold carrier 3 with the support 2 in an upwardly and outwardly inclined position, to thereby insure against accidental dislodgment of the articles 65 stacked.

Support 2, which includes a bottom wall 2', and a top wall 2", is provided with vertical compartments A for reception of the articles in superimposed relation which 70 compartments have open sides (see Fig. 4), facing advancing mechanism, through which the articles are inserted.

Carrier 3 which comprises an open frame is provided on its sides with racks 19 and 75 with outwardly projecting guide ribs 18 which latter are slidably received in the guide ways of swing frame 14 and provided with upper and lower stop pins 25, 25' for engagement with lugs 17', 17", respectively, 80 of a rib 17, to thereby limit vertical movement of the carrier.

Racks 19 which are normally in mesh with pinions 20, are preferably of such length that they will be advanced clear of 85 the said pinions when the desired number of articles have been received in compartments A. Pinions 20 are fixed to a shaft 21, journaled in stand extensions 7^a and driven in common with advancing mechanism 1 by a sprocket chain 22 carried upon sprocket wheels 23, 24 of shafts 21 and 5' respectively.

Support 2 is removably engaged in carrier 3, the same seating on the base 3^a thereof against shoulders 30 and having its top wall 2" apertured for reception of a suitable catch 31, conveniently comprising a bolt slidably mounted in carrier 3 and yieldingly pressed into operative position by a 100 spring 32.

Reference numeral 33 indicates a "take-off," overlying the delivery end portion of mechanism 1 and fixed, in any suitable manner, to stand extensions 7^a. This take-off, 105 whose receiving end portion is preferably tapered and arranged close to or so as to rest on mechanism 1 is inclined downwardly

toward support 2 to facilitate the travel of the articles thereover, as will be readily understood.

The mechanism 1, as above described, is 5 driven by any suitable intermittent motion mechanism.

Articles, as B, placed on mechanism 1 and encountering take-off 33 will be removed by the latter and through their momentum 10 caused to travel thereover into support 2. In this connection, it will be noted that carrier 3 is moved simultaneously with mechanism 1 and each step like movement thereof is of a length corresponding or substantially 15 corresponding to the thickness of an article B. Therefore, the uppermost article stacked will have its upper face substantially flush with the plane of delivery from take-off 33, following the adjustment of carrier 3.

20 When compartments A are filled, advancing mechanism 1 is stopped. The operator now withdraws catch 31, thereby freeing support 2 so that it can be tilted outwardly and lifted from the carrier 3. When so removed it will serve as a tray or temporary holder for the articles. Another support 2 can now be substituted for the one just removed, following which carrier 3 is elevated and the mechanism again set in operation.

30 To elevate carrier 3, swing frame 14 is swung on its pivots 16 to enable the racks 19 clearing the pinions 20. This follows from the fact that the pivot point of swing frame 14 is removed from the center of the axis of 35 the wheel which drives the lowering feed of the carrier. Following this the swing frame is freed so that its weight with that of carrier 3 and support 2 will be imposed through lugs 14^a on stand extensions 7^a at which time 40 racks 19 will be in mesh with pinions 20.

Having thus described our invention, what we claim as new, and desire to secure by Letters Patent of the United States of America, is:—

45 1. In apparatus of the character set forth, article advancing means, a carrier, means for operating the carrier transversely of the direction of movement of the advancing means, a stack holding container detachably supported in the carrier and having a lower interlocking engagement therewith, and a latch for detachably engaging the upper portion of the holding means to secure the same in the carrier.

50 55 2. In apparatus of the character set forth, article advancing means, guideways disposed at the delivery end thereof and extending transversely of the direction of movement of the article by the advancing

means, a reciprocating carrier slidable in the 60 guideways, said carrier having an open rear and front portion, a stack holding tray securable in the opening of said carrier and removable through one side of the carrier, said tray having an open side facing the 65 advancing means, and means for detachably holding the tray in the carrier.

3. In apparatus of the character set forth, stack forming means supported to have a reciprocating and a swinging movement, 70 article advancing means for the stack forming means, and operating means for effecting a reciprocating movement of the stack forming means, said stack forming means being held in engagement with the operating 75 means by gravity and disengaged by said swinging movement.

4. In a device of the kind set forth, a carrier having stack forming compartments, a carrier holding frame having seats for receiving said carrier, means for releasably holding the carrier in its frame, a swingingly mounted guide frame having guiding engagement with the carrier frame conforming to the axes of the stack forming compartments, and a carrier frame feeding means releasable by the swinging of said guide frame.

5. In a device of the kind set forth, a carrier having stack forming compartments, a carrier frame adapted to disengageably receive said carrier, a hinged guide frame, said guide frame and carrier frame having complementary guides conforming in direction 95 with that of the stack forming compartments, means for feeding said carrier frame comprising a rack and gear one on the carrier frame and the other in fixed position and engageable by gravity and disengageable by swinging the guide frame upward.

6. In a device of the kind set forth, article feeding means, a collecting carrier having stack receiving compartments, a carrier frame adapted to support said carrier in position to receive the articles delivered by the feeding means, a guide frame for said carrier frame hinged to one side of said guides, a rack carried by the carrier frame and a feeding gear engaged by said rack by the swinging of the guide frame under the 100 action of gravity thereon.

In testimony whereof we affix our signatures in presence of two witnesses.

WILLIAM J. SWARTZ.
EDWARD H. WAUGH.
